(57) **CLAIM**

The design for a loudspeaker enclosure system having detachable wireless headphones, as shown and described.

DESCRIPTION

FIG. 1 is a front view of a loudspeaker enclosure system having detachable wireless headphones showing the claimed design, of which the fronts (the interior portions facing the loudspeaker enclosure system) of the headphone earphones are not part of the claimed design;

FIG. 2 is a back view thereof;

FIG. 3 is a top view thereof;

FIG. 4 is a bottom view thereof;

FIG. 5 is a left view thereof;

FIG. 6 is a right view thereof;

FIG. 7 is a perspective view thereof; and,

FIG. 8 is an exploded view thereof, with the headphones and speaker detached, the opposite interior face of the headphone being a mirror image.

Portions of the loudspeaker enclosure system having detachable wireless headphones shown in broken lines form no part of the claimed design.
